UNITED STATES PATENT OFFICE.

CLAUDE H. DANIELS, OF NEWTON, MASSACHUSETTS.

SHOE AND PROCESS OF MAKING THE SAME.

Application filed December 11, 1923. Serial No. 680,026.

This invention relates to shoes of the type wherein a welt is employed for assembling the upper with the outer sole, and has as its principal object the provision of a shoe with a maximum degree of flexibility and wherein all the elements, including the innersole, are held securely by stitching. The invention also consists in a new and improved inner-sole adapted for use in the shoe of my invention. In the manufacture of shoes by the ordinary Goodyear welt system, an objection is found particularly in the smaller sizes, for children and ladies, that the lines of stitching which unite the innersole with the welt and the upper and which pass through the innersole at the lip formed thereon, tend to stiffen the sole materially, and greatly reduce and impair the extreme flexibility which is particularly desirable for children's footwear. To avoid this objection shoes have been made wherein the upper is stitched to the welt only, but this has entailed the objection of leaving the innersole practically loose and susceptible of shifting within the shoe, or at best only insecurely held by cementing the same to the upper.

In accordance with my invention I provide an improved innersole that may be assembled in the shoe without stitching to the upper, but which presents a peripheral layer or extending lip that is adapted to be held between the peripheral edge portion of the welt and the outer sole, and securely assembled therewith by through-and-through stitching. I am thus enabled to attain the advantage of extreme flexibility in a shoe wherein all the elements including the inner-sole are held in securely stitched assemblage. The foregoing and other objects and advantages of the invention will more fully appear from the following detailed description taken in connection with the accompanying drawings, and the distinctive features of novelty will be pointed out in the appended claims.

Referring to the drawings:

Fig. 1 is a plan view of an innersole constructed in accordance with my invention;

Fig. 2 is a longitudinal sectional view thereof on line 2—2 of Figure 1;

Fig. 3 is a transverse section through the forward portion of a shoe constructed in accordance with my invention, e. g. on line 3—3 of Figure 4, but on a somewhat enlarged scale; and

Fig. 4 is a side elevation of a shoe con-

structed in accordance with my invention, with the toe portion broken away in section.

In carrying out my invention an innersole 10 is slotted and skived peripherally as indicated at 11, inward a substantial distance 60 so as to provide relatively thin upper and lower peripheral layers 12, 13 respectively, with the lower layer 13, as shown, extending outward farther than the upper layer 12. The upper 14 has the welt 15 stitched there- 65 to as indicated at 16, and is then lasted underneath the upper layer 12 of the innersole, and adhesively secured thereto. This leaves the extending lower layer 13 of the innersole lying against the under side of the welt. 70 In this way, no tacking is necessary for holding the welt to the inner sole, the adhesive cement alone holding the upper and welt securely in the slit opening between the upper and lower layers of the inner sole which 75 embrace the same at either side. This capability of lasting the shoe without tacking is one important feature and advantage of the improved inner sole constituting my invention. The outer sole 17 is then applied with 80 a usual interposed filling layer 18, and the peripheral edge portion of the welt secured to the outer sole with the interposed inner-sole layer 13 by means of through-and- 85 through stitching 19. Thus the innersole is held securely assembled in the shoe with the greatest possible degree of flexibility. In practice the peripheral edge of the innersole layer 13 may be skived down very thin, so as not to show appreciably in the finished shoe, 90 the edge of which is of course finished in the usual manner. I am aware that the invention may be embodied in other specific forms without departing from the spirit or essential attributes thereof, and I therefore desire the 95 present embodiment to be considered in all respects as illustrative and not restrictive, reference being had to the appended claims rather than to the foregoing description to indicate the scope of the invention.

Having described my invention, what I claim as new and desire to secure by Letters Patent is:

1. A shoe of the kind described, comprising an upper, a welt stitched to said upper, an insole member having upper and lower peripheral layers, the upper and welt being lasted and secured between said upper and lower layers, said lower layer extending beyond the upper layer and below the welt, an 105

outsole, and through and through stitching the said upper and lower layers of said insole uniting said outsole, lower insole layer, and with the margin of the upper materials confined between the welt and upper insole layer, 15
welt only, the margin of the upper materials of said shoe being confined between the welt and adhesively uniting the same, applying an outsole thereto, and uniting said outsole, and the upper layer of the insole.

2. The improved process of manufacturing boots and shoes, which consists in uniting upper materials and a welt, slitting an insole lower insole layer and welt by through and member peripherally in such manner that an outsole thereto, and uniting said outsole, 10 an upper and a lower layer will be produced, lasting the assembled upper and welt between

In testimony whereof, I have signed my name to this specification.

CLAUDE H. DANIELS.
